(57) **CLAIM**

The ornamental design for a cross-shaped computer memory device, as shown and described.

DESCRIPTION

FIG. 1 is a three dimensional exploded view of a cross-shaped computer memory device in accordance with the present invention;

FIG. 2 is a front exploded view thereof;

FIG. 3 is a rear exploded view thereof;

FIG. 4 is a side exploded view thereof;

FIG. 5 is a top plan view thereof;

FIG. 6 is a bottom plan view thereof;

FIG. 7 is a front assembled view thereof;

FIG. 8 is a three-dimensional view thereof showing engagement of the cross-shaped computer memory device with a laptop computer;

FIG. 9 is a three dimensional exploded view of a second embodiment of the cross-shaped computer memory device;

FIG. 10 is a front exploded view thereof;

FIG. 11 is a rear exploded view thereof;

FIG. 12 is a side exploded view thereof;

FIG. 13 is a top plan view thereof;

FIG. 14 is a bottom plan view thereof;

FIG. 15 is a front assembled view thereof; and,

FIG. 16 is a three-dimensional view thereof showing engagement of the cross-shaped computer memory device with a laptop computer.

The broken line matter is for illustrative purposes only and forms no part of the claimed design.
